UNITED STATES PATENT OFFICE.

TOBIAS CLEMETSON, OF DULUTH, MINNESOTA.

PACK-SACK.

1,397,161.

Specification of Letters Patent. Patented Nov. 15, 1921.

Application filed March 12, 1920. Serial No. 365,174.

To all whom it may concern:

Be it known that I, TOBIAS CLEMETSON, a citizen of the United States of America, and a resident of Duluth, county of St. Louis, 5 State of Minnesota, have invented certain new and useful Improvements in Pack-Sacks, of which the following is a full and clear specification.

The object of this invention is to provide 10 a simple and durable pack-sack of the knapsack type, as more fully hereinafter set forth.

In the drawing—

Figure 1 is a perspective view looking at 15 the side of the sack which bears against the back of the wearer;

Fig. 2 is a vertical sectional view, with 20 the shoulder-straps shown conventionally extended to better illustrate the strap arrangement.

In the drawing, *a* designates the body of the sack, which consists, as usual, of a casing having its top closed by means of flap *b* which folds downwardly upon the back-wall 25 of the sack. The sack is provided with two shoulder-straps which are affixed to the front-wall near the top thereof by means of an anchoring or reinforcing-strap *c* which is sewed to the front-wall of the sack in 30 such manner as to envelop the ends of the shoulder-straps. These shoulder-straps extend upwardly from the point of anchorage and forwardly, and thence downwardly to form the shoulder-loops *d* through which the 35 arms are inserted when the sack is put on. When the sack is thus put on, the shoulder-loops extend forwardly across the shoulders and downwardly upon the chest of the wearer, the downwardly-extending portions 40 of the shoulder-straps being sewed to the lower portion of the sack. These shoulder-straps preferably extend downwardly on the front-wall of the sack, thence underneath the same, and thence upwardly upon the rear-wall, the straps being stitched or sewed to 45 the front, bottom and rear walls, to thus form a substantial support for the load and prevent the load distorting the sack.

The ends of the shoulder-straps are provided each with a buckle *e*, and extending from each of these buckles upwardly in contact with the depending part of the flap *b* and forwardly across the top of the sack is a load-sustaining and load-shifting strap *f*, the forward free end of which rests upon and is fastened to the shoulder-loops *d*, the

depending end being provided with a loop *g*. The rear depending end of each shoulder-strap is of course detachably and adjustably connected to its buckle, and I provide also 60 for adjustably fastening the front-end of the strap *f* to its shoulder-loop *d*, a series of eyelets *h* being provided in the strap *f* and a locking turn-button *i* being provided on the shoulder-strap *d* so that the effective 65 length of the load-sustaining strap *f* may be varied from time to time. It will be observed that these load-sustaining straps divide the work of supporting the load with the shoulder-straps *d* and also that they hold 70 the mouth of the pack closed. The idea in having the straps adjustably connected to the shoulder-loops is to enable the wearer of the pack to shift the position of the load from time to time, to thereby reduce to a 75 minimum the fatigue from totting the load. By shortening or lengthening the effective length of the straps *f*, the strain of the load will be brought higher or lower upon the back of the wearer, it being obvious that 80 by shortening the effective length of the straps the tendency will be to lift the load so that the pressure thereof on the back of the wearer will be raised, thus bringing the strain upon different muscles or different 85 parts of the same muscles and thus enable the muscles previously in use to recuperate. By thus changing the center of gravity of the load and the point of pressure on the back from time to time, the pack may be 90 toted with much less fatigue than the same load could be carried in an ordinary pack which is so constructed that the pressure and strain of the load remain constant at one point of the back.

In considering this matter of shifting the center of gravity and the point of pressure of the load on the wearer, it will be understood that the sack is made of flexible material and is rarely if ever packed so completely and solidly as to maintain it in a rectangular shape, shown conventionally in Fig. 2, but on the contrary is usually so loosely packed that it can be partially rolled or distorted in shape by pulling up on the 105 load-changing-straps. Actual experience with this pack-sack has demonstrated that, as compared with the ordinary pack-sack, a load can be carried with much less fatigue by reason of the capacity to from time to 110 time shift the position of the load as it bears upon the back of the wearer.

The depending loops *g* are for the purpose of assisting in lifting the pack while it is on the wearer, it being simply necessary to insert the hand in the loop and, after detaching the turn-button *i*, pull down on the strap until the desired eyelet comes in register with the turn-button *i*, whereupon the strap will be locked in its newly adjusted position.

For conveniently carrying the sack in the manner of a suit-case or satchel, I connect the load-lifting straps *f* by means of a bar-like handle *j*, the handle being connected to the strap by loops *k* which are adapted to slide on the straps to thus permit the handle to be adjusted to a point immediately over the center of the sack, irrespective of the adjustment of the load-straps.

I prefer making the sack as well as all of the straps out of a fabric, such as duck, canvas, etc., so that the sack may be readily washed as a whole, to thus keep it in a sanitary condition. In view of the fact that these sacks are frequently used for carrying food articles, this ability to give the sack a tub-wash is a very important advantage. Of course, in washing the sack, the load-straps *f* may be removed if it is desired to do so.

The use of a textile fabric, thereby doing away with all leather in the appliance, greatly reduces its cost of manufacture, as is obvious. It will be observed also that the idea of adjustably buckling the ends of the load-straps at the back is an advantage, in

that it enables me to extend the straps to the limit and thus permit the sack to be filled to capacity; and it will be observed further that these load-straps avoid the necessity for using special straps or fastenings for the cover.

The nature and scope of the invention having been thus indicated and the preferred embodiment having been specifically described, what is claimed as new is:

A pack-sack consisting of a flexible receptacle having a closure flap at its upper end adapted to fold down on the rear side of the receptacle, a pair of shoulder-straps fastened to the front side of the receptacle and extending down the front side and around the under side and up the rear side of the receptacle, to which side the shoulder-straps are fastened, each of the upwardly-extending ends of the straps being provided with a buckle, and a pair of load-sustaining and load-shifting straps adjustably connected to said buckles and extending upwardly and forwardly over the top of the receptacle, and means for adjustably attaching these straps to the front sides of the shoulder-straps, for the purpose set forth.

In testimony whereof I hereunto affix my signature.

TOBIAS CLEMETSON.
